UNITED STATES PATENT OFFICE.

RAY BUTLER, OF CINCINNATI, OHIO.

KEY-RING HOOK.

1,198,105.

Specification of Letters Patent. Patented Sept. 12, 1916.

Application filed November 18, 1914. Serial No. 872,731.

To all whom it may concern:

Be it known that I, RAY BUTLER, a citizen of the United States, residing at Cincinnati, in the county of Hamilton and State of Ohio, have invented new and useful Improvements in Key-Ring Hooks, of which the following is a specification.

This invention relates to key ring hooks or holders and the object in view is to produce a device of the character specified which will serve as an absolute guarantee and protection against a key ring or the like becoming detached therefrom and which at the same time will admit of the ready insertion and removal of the key ring relatively to the hook or support with the aid of one hand only and this operation may be easily effected even when the hand of the operator is covered by a glove, mitt or the like thus particularly adapting the device for use in cold weather and by persons such as the drivers of teams, automobiles and the like. It is practically impossible for the key ring to detach itself from the hook or holder either accidentally or when a pulling strain is surreptitiously placed thereon.

With the above and other objects in view, the invention consists in the novel construction, combination and arrangement of parts, as herein described, illustrated and claimed.

In the accompanying drawings: Figure 1 is an edge view of the key ring hook of this invention shown applied to a belt or waist band and also showing a key ring and the portion of a key chain attached thereto. Fig. 2 is a perspective view of the key ring hook showing the ring in its normal position therein. Fig. 3 is a perspective view of the key ring hook illustrating the manner of removing the key ring therefrom. Fig. 4 is a similar view showing the manner of inserting the key ring in the hook.

The key ring hook of this invention is formed in one piece, the same being shown; in the preferred embodiment of this invention, as consisting of a flat strip of spring metal the same being bent as shown in the drawings to comprise a garment or belt engaging loop 1 which is split or divided at the lower end where one extremity of the loop is left comparatively free so that it may be slipped over a belt or waist band indicated at 2 in cross section.

After forming the loop 1, the strip is bent to form a ring holding or supporting hook designated generally at A and comprising

the back or main body 3 which extends downwardly from the loop or clasp 1 and the upwardly extending end portion or bill 4. The portion 4 of the hook extends upwardly on one side of the loop or clasp 1 and the end portion of the strip after forming the bill 4 is bent backwardly and extended downwardly in convergent relation to the adjacent side of the clasp 1 forming a spring guard 5 the extremity 6 of which rests against the clasp adjacent to the point of junction between the clasp and hook.

At the point of junction of the clasp and hook, the strip is bent in ogee shape to form a curved shoulder 7 and the free end portion of the loop or clasp 1 is crimped as shown at 8 to provide an inwardly extending offset which normally rests against and conforms in curvature to the shoulder 7. The extremity of this portion of the strip is deflected outwardly as shown at 9 so as to facilitate placing the clasp over a belt, waist band or other portion of a garment as indicated in Fig. 1.

In order to insert a key ring designated at 10 in the hook, said ring is brought into the relation to the hook illustrated in Fig. 4, a part of the ring being inserted between the guard 5 and the adjacent side of the clasp or loop 1. Force is then applied in a downward direction to the ring 10, whereupon it displaces the extremity 6 of the guard and passes by the same into the hook A. In order to remove the ring 10, a portion of said ring is introduced between the guard 5 and clasp 1 in the manner illustrated in Fig. 3. Force is then applied in a downward direction in order to press the extremity of the guard away from the clasp and simultaneously with such movement, the ring 10 is forced to one side as indicated in Fig. 3, resulting in the ring escaping from between the guard and clasp. Thus the ring 10 is inserted in and removed from the hook by applying force to said ring in a downward direction. When the ring 10 is in its final position as illustrated in Figs. 1 and 2, it is practically impossible for the ring to escape from the hook either accidentally or when force is applied thereto in any other way than that above described.

What I claim is:

A one piece key ring holder consisting of a single spring strip of uniform width from end to end so bent as to form and comprise a split garment-engaging clasp, a hook ex-

tending downwardly from said clasp and having an upwardly projecting bill located at one side of said clasp, and a substantially straight guard forming a return portion of the bill of the hook and uniformly diverging downwardly from the point of the bill, the base of the hook being provided with an ogee shaped bend forming a curved key ring deflecting shoulder at the junction of the 10 clasp and hook, the free end portion of the clasp being crimped to form an inwardly

projecting offset which rests against the opposite side of said shoulder, the free extremity of the guard normally resting against the outer side of the clasp adjacent 15 to the upper part of said shoulder.

In testimony whereof I affix my signature in presence of two witnesses,

RAY BUTLER.
